UNITED STATES PATENT OFFICE.

CIPRIANO ANDRADE, JR., OF NEW YORK, N. Y.

AUTOMATIC REEFING BOOM.

Application filed April 11, 1927. Serial No. 182,563.

My invention relates to an automatic reefing boom adapted to either reef or furl a sail on a boat automatically.

I attain this object by the mechanism illustrated in the accompanying drawings, in which:

Fig. 1 is a side view of my device on a sail boat; Fig. 2 is an end view of the rotatable holder W; Fig. 3 is a sectional side view at the mast end of a portion of my automatic reefing boom with its various connected elements; Fig. 4 is a sectional side view of the outer end of a portion of my automatic reefing boom with its various connected elements; Fig. 5 is a sectional side view of a portion of my outer element P, with the lengthwise coiled circular spring A and the inside element P⁶ shown in circumferential form; Fig. 6 is an outer end view 20 of the connecting element P¹¹; Fig. 7 is a side view of said connecting element P¹¹; Fig. 8 is an outer end view of the holder P²⁰; Fig. 9 is a side view of said holder P²⁰; Fig. 10 is an end view of the intermediate element P⁸; Fig. 11 is a side view of the gooseneck holder V²; Fig. 12 is an end view of said gooseneck holder V²; and Fig. 13 is a sectional side view of a portion of my automatic reefing boom in alternate construction.

Similar letters and numerals refer to similar parts throughout the several views:

M is the load water line; N is the hull; O is the mast; P is the outer element of the automatic reefing boom; Q are the outer surfaces of the mainsail B when full set; Q¹ are the outer surfaces of the mainsail B when partially reefed; Q² are the outer surfaces of the mainsail B when further partially reefed; Z is the centre of effort of the mainsail B in Q position; Z¹ is the centre of effort of the mainsail B in Q¹ position; Z² is the centre of effort of the mainsail B in Q² position; R is the mainsheet; S is the boom lift; T is the forestay; U is the sail halyard; V is the gooseneck; W is the rotatable holder against the outer end of the automatic reefing boom to hold boom lift S and mainsheet R in the same position whether the outer element P is rotating one way or the other; W¹ is the hole in holder W to hold boom lift S; W² is the hole in holder W to hold mainsheet R; P¹ is a circular element fastened tightly to the inner surface of the outer element P by screws, bolts or any equivalent means, said element P¹ is rotatable with relation to rotatable holder W; P³ is the end of circular element P¹; P² is the outer surface of P³, and P² being rotatable with relation to rotatable holder W; P⁴ is a 60 first intermediate element rigidly attached to outer element P, said first intermediate element P⁴ being freely rotatable over the inside element P⁶; A is a lengthwise coiled circular spring, one end of which is rigidly attached to the end surface P⁵ of said first intermediate element P⁴, and the other end of said lengthwise coiled circular spring A is rigidly attached to the end surface P¹⁰ of a second intermediate element P⁷; P⁷ is 70 a second intermediate element rigidly attached to inside element P⁶, said second intermediate element P⁷ allowing free rotation of outer element P; P⁸ is a third intermediate element rigidly attached to the inner surface of outer element P, said third intermediate element P⁸ being freely rotatable over the outer surface of inside element P⁶, said third intermediate element P⁸ being 75 in free side rotatable contact with said second intermediate element P⁷; P⁹ is a fourth intermediate element rigidly attached to inside element P⁶, said fourth intermediate element P⁹ allowing free rotation of outer element P, said fourth intermediate element P⁹ being in free side contact with said third intermediate element P⁸; P¹¹ is a connecting element rigidly attached to inside element P⁶; P¹⁵ is a part of connecting element P¹¹, having a circular hole P¹⁶, and having 80 flat end surfaces P¹² and P¹³ and flat top surface P¹⁷; P²⁰ is a holder which can move freely into the holes P³⁰ in intermediate elements P⁹, P⁸ and P⁷; P²¹ is a part of holder P²⁰, said P²¹ being adapted to drop against 85 flat end surface P¹² when said holder P²⁰ is entirely inside of all three holes P³⁰ in intermediate elements P⁹, P⁸ and P⁷, and said P²¹ being also adapted to drop against flat end surface P¹⁸ when said holder P²⁰ is 90 partly pulled out, so that it is inside of only the one hole P³⁰ in intermediate element P⁹ only; P⁴⁰ is the hole in intermediate elements P⁹, P⁸ and P⁷, said hole P⁴⁰ being 95 on the outer surface of inside element P⁶; V¹ is the inside round hole in gooseneck V to hold tightly over mast O; V² is the gooseneck holder with a lower round part V³ which is rotatable sideways in gooseneck V; V⁴ is a hole in V³ to hold a bolt or any sim- 100 105 110

ilar means to prevent V^s from lifting up out of gooseneck V ; V^s is the upper portion of V^2 adapted to hold element P^{15} therein; V^6 is a circular hole in V^s in alignment with circular hole P^{16} of element P^{15} , whereby a bolt or any similar means will hold element P^{15} inside of element V^s , and will permit connecting element P^{11} to move up or down radially from the centre of P^{16} ; P^{41} is an alternate form of my first intermediate element P^4 rigidly attached to outer element P ; P^{42} is a preferably flat sided end element of P^{41} rigidly fitted into wooden boom section P^{43} , and adapted to hold said section P^{43} from rotating with relation to outer element P . Said element P^{42} is of course not absolutely essential, as bolts or other similar devices could fasten wooden boom section P^{43} direct to outer element P .

It will be noted that preferably the inner surface of outer element P is circular; and that preferably the outer surface of inside element P^6 is circular; and that preferably the intermediate elements P^4 , P^7 , P^8 and P^9 are circular, although they could function even if not circular.

It will also be noted that elements P , P^6 , P^4 , P^7 , P^8 or P^{41} are preferably of metal, although they could function even if made of wood or other substances. In the form shown in Fig. 13 the elements P , P^{41} with its end element P^{42} would preferably be made of metal, with the element P^{43} preferably of wood, although as stated these various elements could be made of other substances. It will also be understood that preferably the lengthwise coiled circular spring A will be only a fraction of the length of the entire automatic reefing boom, and therefore the form of construction shown in Fig. 13 will be perhaps preferable to an outer element P made the full length of the automatic reefing boom, and when this is done, the rotatable holder W can be so arranged on the outer end of P^{43} of the automatic reefing boom that said rotatable holder W will function as hereinbefore stated.

The operation of my device is as follows:

As the intermediate element P^8 is rigidly attached to the outer element P , and as the intermediate elements P^7 and P^9 are rigidly attached to inside element P^6 , and as the connecting element P^{11} is also rigidly attached to inside element P^6 , and as the connecting element P^{11} is fastened by a bolt or any similar means to the gooseneck holder V^2 , it will be noted that both the inside element P^6 and the outer element P are always held in endwise position in relation to each other, and cannot move either away from or toward the gooseneck V or the mast O ; and also it will be noted that by means of the lower round part V^3 , the outer element P can move either way sidewise radially from the centre of said lower round part V^3 ;

and also it will be noted that by means of the bolt or any similar means in the circular holes V^6 and P^{16} , the outer element P can move either up or down radially from the centre of said circular holes V^6 and P^{16} ; which allows the automatic reefing boom the normal motion of any standard boom in any sailboat. It will also be noted that as the inside element P^6 is rigidly attached to the connecting element P^{11} , said inside element P^6 can never move circumferentially; and as intermediate elements P^7 and P^9 are rigidly attached to inside element P^6 , said intermediate elements P^7 and P^9 can never move circumferentially. And as intermediate elements P^4 and P^8 are rigidly attached to outer element P , but are not rigidly attached to circular inside element P^6 , it will be noted that outer element P can rotate freely in relation to inside element P^6 , except when holder P^{20} is put into the hole P^{30} in intermediate element P^8 as shown in Fig. 3 hereof. And as the lengthwise coiled circular spring A is rigidly attached at one end to end surface P^5 of intermediate element P^4 , and as the other end of said lengthwise coiled circular spring A is rigidly attached to the end surface P^{10} of intermediate element P^7 , it will be noted that said lengthwise coiled circular spring A will control the rotative motion of outer element P with relation to inside element P^6 when the holder P^{20} is pulled out by hand or otherwise, so as to clear the hole P^{30} in intermediate element P^8 . In order to pull out said holder P^{20} as just stated, it will be noted that the element P^{21} thereof must be turned around upward into the top position as shown in Figs. 3, 8 and 9 hereof, so that said element P^{21} can move over the flat top surface P^{17} of element P^{15} ; and when holder P^{20} is thus pulled out from hole P^{30} of intermediate element P^8 , but is left in hole P^{30} of intermediate element P^9 and is released, the element P^{21} thereof will drop down circumferentially against the flat end surface P^{13} of element P^{15} , which will make it impossible for holder P^{20} to get back into hole P^{30} in intermediate element P^8 , until said element P^{21} is turned around upward into the top position as shown in Figs. 8 and 9 hereof. And when the rotative motion of outer element P with relation to inside element P^6 is desired to be stopped, the element P^{21} of holder P^{20} as just stated can be turned around upward into the top position as shown in Figs. 8 and 9 hereof, and holder P^{20} can then be pushed into holes P^{30} of intermediate elements P^8 and P^7 as shown in Fig. 3 hereof; and when said element P^{21} is then released, said element P^{21} will drop down circumferentially against the flat end surface P^{12} of element P^{15} , which will make it impossible for holder P^{20} to move out from holes P^{30} in intermediate elements P^7 , P^8

or P^9 , until said element P^{21} is turned around upward into the top position as shown in Fig. 3 hereof.

Let us now assume that the mainsail B is full set as shown in Fig. 1 hereof, and that it is desired to reef it down to the position Q^1 . The first thing to do is to pull holder P^{20} out of holes P^{30} in intermediate elements P^7 and P^8 , and then to let element P^{21} drop down against the flat end surface P^{18} of element P^{15} . Then loosen sail halyard U, whereupon the lengthwise coiled circular spring A will cause outer element P, which is attached to the foot of mainsail B, to rotate, thus automatically winding the lower end of mainsail B around the outer surface of the automatic reefing boom. And when sail halyard U has been sufficiently released to bring mainsail B down to the position Q^1 , the halyard U should be held motionless, and holder P^{20} should be pushed back into holes P^{30} in intermediate elements P^8 and P^7 , and element P^{21} should be dropped down against the flat end surface P^{12} of element P^{15} , then halyard U should be made fast, whereupon the reefing is entirely completed.

If it is then desired to furl the mainsail B, holder P^{20} should be pulled out of holes P^{30} in intermediate elements P^7 and P^8 , and element P^{21} should be dropped down against the flat end surface P^{18} of element P^{15} . Then sail halyard U should be let go, whereupon the lengthwise coiled circular spring A will cause outer element P to wind the entire mainsail B around the outer surface of the automatic reefing boom. Then holder P^{20} should be pushed back into holes P^{30} in intermediate elements P^8 and P^7 , and halyard U should be made fast, whereupon the furling is entirely completed.

In order to raise the sail B, all that is necessary to do is to pull holder P^{20} out, until it is clear of holes P^{30} of intermediate elements P^7 and P^8 , and then pull the sail B up by halyard U, and then push the holder P^{20} back into holes P^{30} of intermediate elements P^8 and P^7 , and then make fast the lower end of halyard U. While thus raising the sail B, the mainsheet R should of course be made fast so as to keep the automatic reefing boom from being raised at its after end.

It will be noted that, when holder P^{20} is placed in holes P^{30} of intermediate elements P^9 , P^8 and P^7 , the circumferential pressure of the lengthwise coiled circular spring A ceases to act on outer element P; which relieves the sail B and the halyard U from any abnormal downward pulling pressure, and which also prevents the sail B from being able to rotate the automatic reefing boom when a heavy wind strikes the sail B.

Boomlift S will always hold the automatic reefing boom in the same position as shown in Fig. 1, and will thus prevent the after end

of said automatic reefing boom from dropping down when sail halyard U is unloosened. As stated, rotatable holder W is so fitted to the after end of the automatic reefing boom that said automatic reefing boom can rotate freely with relation to said rotatable holder W, while said rotatable holder W can remain without any rotation.

The advantage of the form of mainsail B free from the mast O as shown in Fig. 1 hereof, is that it will not put the mainsail centre of effort Z too far forward at any time. It will thus permit the mainsail B to keep its centre of effort Z practically in the same fore and aft position whether the mainsail B is in full area or reefed for heavy weather, as shown in Q^1 or Q^2 of Fig. 1 hereof.

It will of course be understood that the exact relation of the parts hereinbefore described can be modified by mechanical equivalents thereof, without changing the essential elements of my invention. For example similar results could be obtained by making the intermediate elements P^4 and P^8 rigidly attached to inside element P^6 , and freely rotatable inside the outer element P; and by making the intermediate elements P^7 and P^9 rigidly attached to outer element P, and freely rotatable over the inside element P^6 .

It will also be understood that the fourth intermediate element P^9 could be made integral with connecting element P^{11} , in which case the end of inside element P^6 would stop at the inner end of said intermediate element P^9 .

It will also be understood that, if desired, the holder P^{20} could be removed not only from holes P^{30} of intermediate elements P^7 and P^8 but also from hole P^{30} of intermediate element P^9 ; which will be understood in the specification and all the claims hereof.

It will be noted that my automatic reefing boom can be used for a jib, a foresail, a mainsail, a mizzen sail, a topsail or any other known form of sail, or whether said sail is of the marconi type as shown in Fig. 1 hereof, or whether said sail has a gaff. And if desired, the forward edge of the sail could be fastened to the mast or to the forestay by a movable line or any similar means which would permit the sail to wind around the outer surface of the automatic reefing boom in the relative positions shown in Fig. 1 hereof or otherwise.

I claim:

1. In an automatic reefing boom; an inside element held in nonrotatable position; an outer element; a first intermediate element rigidly attached to the inner surface of said outer element, said first intermediate element being freely rotatable over the outer surface of said inside element; a second intermediate element rigidly attached to the outer surface of said inside element, said

- second intermediate element allowing free rotation of said outer element; a lengthwise coiled circular spring, one end of said lengthwise coiled circular spring being attached rigidly to said first intermediate element, and the other end of said lengthwise coiled circular spring being attached rigidly to said second intermediate element; a third intermediate element rigidly attached to the inner surface of said outer element, said third intermediate element being freely rotatable over the outer surface of said inside element, said third intermediate element being in free side rotatable contact with said second intermediate element; a fourth intermediate element rigidly attached to the outer surface of said inside element, said fourth intermediate element allowing free rotation of said outer element, said fourth intermediate element being in free side contact with said third intermediate element; holes axially alignable with each other in said second, third and fourth intermediate elements; and a holder adapted to enter into said holes in said second, third and fourth intermediate elements or to be removed from said holes in said second and third intermediate elements.
2. In an automatic reefing boom; an inside element; an outer element; a connecting element rigidly attached to said inside element, and adapted to hold said inside element in nonrotatable position, said connecting element having a flat end surface and also an opposite flat end surface and also a flat top surface; an intermediate element rigidly attached to the outer surface of said inside element, said intermediate element allowing free rotation of said outer element; an intermediate element rigidly attached to the inner surface of said outer element, said intermediate element being rotatable over the outer surface of said inside element; holes axially alignable with each other in said two intermediate elements; and a holder adapted to enter into said holes in said two intermediate elements, or to be removed from said hole in one or both of said intermediate elements, said holder having a part adapted to drop endwise against the flat end surface of said connecting element, said part of said holder being also adapted to drop endwise against the opposite flat end surface of said connecting element, said part of said holder being also adapted to move endwise over the flat top surface of said connecting element.
3. In an automatic reefing boom; an inside element; an outer element; a connecting element rigidly attached to said inside element, and adapted to hold said inside element in nonrotatable position, said connecting element having a flat end surface and also an opposite flat end surface and also a flat top surface; three intermediate elements adapted to permit said outer element to ro-
- tate in relation to said inside element, said three intermediate elements being also adapted to prevent said outer element to move endwise in either direction in relation to said inside element; holes axially alignable with each other in each of said three intermediate elements; and a holder adapted to enter into said holes in said three intermediate elements whereby said outer element will be unable to rotate in relation to said inside element, said holder being also adapted to be removed from two of said holes whereby said outer element will be able to rotate in relation to said inside element, said holder having a part adapted to drop endwise against the flat end surface of said connecting element, said part of said holder being also adapted to drop endwise against the opposite flat end surface of said connecting element, said part of said holder being also adapted to move endwise over the flat top surface of said connecting element.
4. In an automatic reefing boom; an inside element; an outer element; a connecting element rigidly attached to said inside element, and adapted to hold said inside element in nonrotatable position, said connecting element having a flat end surface and also an opposite flat end surface and also a flat top surface; a first intermediate element rigidly attached to the inner surface of said outer element, said first intermediate element being freely rotatable over the outer surface of said inside element; a second intermediate element rigidly attached to the outer surface of said inside element, said second intermediate element allowing free rotation of said outer element; a lengthwise coiled circular spring, one end of said lengthwise coiled circular spring being attached rigidly to said first intermediate element, and the other end of said lengthwise coiled circular spring being attached rigidly to said second intermediate element; a third intermediate element rigidly attached to the inner surface of said outer element, said third intermediate element being freely rotatable over the outer surface of said inside element, said third intermediate element being in free side rotatable contact with said second intermediate element; a fourth intermediate element rigidly attached to the outer surface of said inside element, said fourth intermediate element allowing free rotation of said outer element, said fourth intermediate element being in free side contact with said third intermediate element; holes axially alignable with each other in said second, third and fourth intermediate elements; and a holder adapted to enter into said holes in said second, third and fourth intermediate elements, or to be removed from said holes in said second and third intermediate elements, said holder having a part adapted to drop endwise against the flat end surface of said connecting element.

said connecting element, said part of said holder being also adapted to drop endwise against the opposite flat end surface of said connecting element, said part of said round 5 holder being also adapted to move endwise over the flat top surface of said connecting element.

5. In an automatic reefing boom; an inside element; an outer element; three intermediate elements adapted to permit said outer element to rotate in relation to said inside element, said three intermediate elements being also adapted to prevent said outer element to move endwise in either direction in relation to said inside element; 15 holes axially alignable with each other in each of said three intermediate elements; and a holder adapted to enter into said holes in said three intermediate elements whereby 20 said outer element will be unable to rotate in relation to said inside element, said holder being also adapted to be removed from two of said holes whereby said outer element will be able to rotate in relation to said inside 25 element.

6. In an automatic reefing boom; an inside element; an outer element; a spring coiled endwise and circumferentially rotatable adapted to rotate said outer element in 30 relation to said inside element; and means, whereby said outer element can become non-rotatable both forward and reverse in relation to said inside element, and whereby said outer element can also become freely rotat-

able either forward or reverse in relation to 35 said inside element.

7. In an automatic reefing boom; an inside element; an outer element; and a spring coiled endwise and circumferentially rotatable adapted to rotate said outer element; 40 said automatic reefing boom having one end held in position whereby said one end cannot move either up or down or sideways, and the other end of said automatic reefing boom being able to move sideways and up and 45 down.

8. In an automatic reefing boom; an inside element; an outer element; and a spring coiled endwise and circumferentially rotatable adapted to rotate said outer element; 50 said automatic reefing boom being attached to a sail, one end of said automatic reefing boom being attached to a mast, and the other end of said automatic reefing boom being able to move sideways and up and down. 55

9. In an automatic reefing boom; an inside element; an outer element; a spring placed between said inside element and said outer element, said spring being adapted to rotate said outer element in relation to said inside element; and means, whereby said outer element can become nonrotatable both forward and reverse in relation to said inside element, and whereby said outer element can also become freely rotatable either 60 forward or reverse in relation to said inside element. 65

CIPRIANO ANDRADE, JR.
